LOUDSPEAKER ENCLOSURES

Alfred H. Roberts, 1615 Monk Road, Gladwyne, Pa.
Filed Feb. 8, 1961, Ser. No. 87,909
1 Claim. (Cl. 181—31)

This invention relates to loudspeaker enclosures.

In my prior application for patent for loudspeaker enclosures, Serial No. 803,856, filed April 3, 1959, now U.S. Patent No. 2,978,060, there is disclosed a loudspeaker enclosure which has certain properties of a horn, of a Helmholtz resonator or bass-reflex enclosure, and of a pipe folded once, but which does not satisfy all the criteria for any one of these three types of couplers.

In accordance with the present invention, a loudspeaker enclosure is provided which has some features in common with the enclosure of my prior application, but which involves simplifications and improvements and is particularly suitable for use as a stereophonic device.

The essential differences with respect to the loudspeaker enclosure of my prior application are: (1) the capability of using a single wide range speaker with consequent reduction in cost, (2) the coaction of the supporting panel with the wall and floor to form a corner-horn type of mouth improves the loading upon the speaker in the bass range, (3) the downward disposition of the mouth which permits of transmitting the uttermost low notes through coupling to the floor, (4) the quarter wave air column is extended outwardly to the terminus of the mouth, reducing the anti-resonant frequency with consequent extension of the bass range, (5) the area of the mouth terminus may be controlled by employing the correct elevation of the superstructure from the floor so that the area of the mouth terminus can be made either equal or greater than the area of the intermediate passage with consequent increase in radiated sound power, (6) the structure is compact and convenient for use in the home, and (7) the enclosure is particularly suited for use as a stereophonic device.

It is the principal object of the present invention to provide a loudspeaker enclosure having an improved low audible frequency response which is economical of space and materials.

It is a further object of the present invention to provide a loudspeaker enclosure which is efficient in the reproduction of sound yet is capable of operation with loudspeakers having diverse operational properties.

It is a further object of the present invention to provide a loudspeaker enclosure in which the speaker is supported by a panel which functions with the wall and floor of the room in which the enclosure is used to provide an improved type of discharge.

It is a further object of the present invention to provide a loudspeaker enclosure in which a preferred embodiment has provisions for the direct delivery of the speaker output on one side of the speaker and indirect delivery from the other face of the diaphragm through an elongated path which includes an energy sink.

Other objects and advantageous features of the invention will be apparent from the description and claim.

The nature and characteristic features of the invention will be more readily understood from the following description, taken in connection with the accompanying drawings forming part thereof, in which:

FIGURE 1 is a vertical central sectional view of a preferred embodiment of the invention taken approximately on the line 1—1 of FIG. 2;

FIG. 2 is an end elevational view of the loudspeaker enclosure of FIG. 1 as seen from the right hand end;

FIG. 3 is a front elevational view of another preferred embodiment of the invention with the speaker facing in a forward direction;

2

FIG. 4 is a vertical sectional view taken approximately on the line 4—4 of FIG. 3;

FIG. 5 is a diagrammatic view of the acoustical circuit as represented by the approximate electrical analogs; and

FIG. 6 is a diagrammatic view showing the variation with frequency of the motional impedance of the loudspeaker housed in the loudspeaker enclosure of the present invention.

It should, of course, be understood that the description and drawings herein are illustrative merely, and that various modifications and changes can be made in the structure disclosed without departing from the spirit of the invention.

Like numerals refer to like parts throughout the several views.

Referring now more particularly to FIGS. 1 and 2 of the drawings in which a preferred embodiment of the invention is illustrated, a pair of loudspeaker enclosures is shown as disposed at opposite ends or sides of a cabinet RPC in which a record player (not shown) or the like may be disposed.

Each of the enclosures in accordance with the invention and in a practical and useful embodiment can have an exterior width of the order of 14 to 18 inches, an exterior depth of the same order, and a total height in feet of

$$\frac{120}{f_0} + \frac{1}{2}$$

where f_0 is the primary resonance of the loudspeaker in free air in cycles per second.

The enclosure preferably includes a horizontal top wall panel 10, and vertical side wall panels connected to and extending downwardly from said top wall panel 10 and including vertical front and rear wall panels 11 and 12, an inner vertical end wall panel 13, and an outer vertical exterior or end wall panel 15. The panel 12 may be advantageously disposed against the vertical wall 14 of a room or other enclosure and the panel 13 extends downwardly to the floor on which the enclosure is supported and with the other panel 13 of the other speaker enclosure can serve as a support. The panel 13 is preferably of a width to serve as a baffle and with the wall 14 closes two vertical sides of the space below the enclosure.

An interior baffle is provided which includes a baffle panel 16 extending inwardly and upwardly at an inclination with respect to the lower terminus of the panel 15, extends between the vertical wall panels 11 and 12 and has an inclined panel 17 extending upwardly therefrom which also extends to and between the panels 11 and 12. The panels 10, 11, 12, 15, 16 and 17 may be made of any desired material, such as wood, plywood, veneered chipboard, and the like and panels of a thickness of three-quarters of an inch have been found satisfactory.

The vertical supporting panel 13 may be made of the same material as the panels just referred to, but is preferably of double thickness.

The interior of the enclosure preferably has reinforcing framing members 18 horizontally disposed therein. The panels, at their meeting margins, are preferably secured together in any desired manner so as to be rigid and airtight therealong.

As shown in FIGS. 1 and 2, the exterior panel 15 has a loudspeaker diaphragm opening 19 therethrough and is adapted to support a loudspeaker 20 secured thereto in any desired manner with one surface 20a of the speaker diaphragm facing outwardly and the other surface 20b being faced inwardly.

The loudspeaker 20 may be of any preferred type such as an electro-magnetic or an electro-static speaker.

The loudspeaker 20 has a damping ring 21 of any

suitable material applied thereto and held thereon. The damping ring 21 may be of any desired construction but for the purposes of the present invention, a damping ring similar to that shown in the application above identified is preferably employed consisting of a ring 40 of glass wool snugly fitted within a cowl 41.

The space within the wall panels 11, 12 and 15 and the supporting panel 13 has an interior throat portion 30 bounded by the baffles 16 and 17, and the lower portions of the wall panels 11, 12 and 15. The space within the wall panels 11, 12, 13 and 15 also includes a space 31, functioning as an energy sink, communicating with the throat portion 30 and bounded by the top panel 10 and upper portions of the panels 11, 12, 13 and 15. The space within the wall panels 11, 12 and 15, and the supporting panel 13 also includes an intermediate passage portion 35 extending downward from the energy sink 31 and is bounded by the baffles 16 and 17 and the lower portions of the panels 11, 12 and 13, and communicates through a mouth portion 32 with the outer air, the mouth terminus 32a lying in the planes of the panels 11 and 15 projected downwardly to the floor 14a of the room.

For monaural systems a speaker enclosure at only one end of the cabinet RPC will suffice, but for stereophonic use, two spaced enclosures are provided with a phono-radio compartment RPC therebetween.

Referring now to FIGS. 3 and 4, another orientation of the loud speaker 20 is shown with the speaker 20 facing away from the wall 14 of the room, with a horizontal baffle panel 16a and inclined baffle panel 17a and with an opening or aperture 19b in the front wall panel 11a at which one face of the diaphragm of the loudspeaker 20 is exposed.

Reference will now be had to the acoustical properties of the enclosure in accordance with the present invention.

The enclosure in accordance with the invention makes use of the quarter-wave action of a folded air column to establish an anti-resonance at and near the primary free air resonance frequency of a loudspeaker. In this respect, the enclosure resembles an organ pipe closed at one end and folded once.

The proportions of the air column, most particularly at the fold, are, however, incompatible with those of an organ pipe or resonant tube and are in fact more those of a box. Above the top edge of the interior baffle 17 and bounded by panels 10, 11, 12, 13 and 15 there exists an elastic volume of air which functions as an energy sink 31 at the antiresonance frequency. In this respect, the present invention resembles the Helmholtz resonator, which is also known in one of its forms as the bass-reflex enclosure.

At the inner end of the air column the interior throat portion 30 is located, and at the outer end, beyond the mouth portion 32, lies the mouth terminus 32a, peripheral to the solid angle defined by the room wall 14, the floor 14a and the lower part of the panel 13, and lying in the planes of panels 11 and 15, as previously described. The mouth terminus 32a encompasses an area several times that of the interior throat portion 30, the latter area taken horizontally, and the ratio of these areas multiplies, by impedance transformation, the useful load upon the loudspeaker diaphragm surface 20b of FIG. 1. In this respect, the present invention resembles a small corner horn of the type familiar in this art.

Considered as a pipe, the enclosure in accordance with the present invention is disqualified, however, by reason of the large reactive impedance at the fold (the energy sink 31) and by reason of the flared orifice at the outer end of the air column.

Considered as a Helmholtz resonator, the enclosure in accordance with the present invention is disqualified because the antiresonance is established by the length of the air column, rather than by restriction of area as in the vent of a bass-reflex enclosure. Within the energy

sink 31, the air column and the compliant air volume are coterminous and in effect vibrate in two modes.

Considered as a horn, the enclosure in accordance with the present invention is disqualified (1) by the pronounced quarter-wave antiresonance of the air column and (2) by the shortness of the air column with respect to the wavelengths transmitted. Horns must encompass at least several wavelengths from throat to mouth; and any air column, no matter what its flare, becomes a simple discontinuity at its outer end when shorter in length than a quarter wave. (See L. L. Beranek, Acoustics, McGraw-Hill Book Co., 1954; page 272.)

Undesired resonances, both longitudinal and transverse, must be avoided and these may be eliminated or suppressed (1) by diverting higher frequencies from the loudspeaker by means of an electrical crossover network, (2) by proper design of the damping ring, which discriminates against higher frequencies, and (3) by placement of acoustically absorbent material within the interior throat portion and/or energy sink portion of the coupler, either as a blanket lining or a stuffing, and (4) by the inherent character of the invention, wherein the transverse dimensions become comparable to a wavelength at frequencies within the lower midrange of audibility, thus giving rise to dissonant weaker resonances in several modes and in turn smoothing the frequency response.

The present structure is a three-way acoustical hybrid whose behavior is regulated (1) by its structure and proportions and (2) by the use of dissipative damping.

The electrical analogs shown in FIG. 5 aid in understanding the operation of the present invention, making clear its differences from the enclosures heretofore available.

Referring now more particularly to FIG. 5, the acoustical properties of the present invention are described in the electrical impedance analog as follows:

C_s =Compliance of the elastic suspension of the loudspeaker diaphragm

R_s =Resistance of the speaker suspension lumped with radiation resistance encountered by the face of the diaphragm 20a

M_s =Inertance of loudspeaker moving system lumped with that of the air lying immediately in front of the diaphragm 20a

R_d =Dissipative resistance introduced close to the diaphragm 20 by acoustically absorbent material such as damping ring 21

P_c =Acoustical pressure acting upon the transmission network

50 U_c =Volume velocity produced by P_c
 M_t =Inertance of interior throat portion 30

R_b =Dissipative resistance within energy sink 31

C_b =Compliance of air volume within energy sink 31

M_m =Inertance of mouth portion 32 and mouth terminus 32a

R_a =Radiation resistance at mouth terminus 32a

U_b =Volume velocity through energy sink 31

U_a =Volume velocity through mouth terminus 32a

60 R_a and R_d vary approximately with the second power of the frequency at the frequencies of interest (i.e., below 500 c.p.s.).

It is apparent that the network $M_t R_b C_b M_m$ is a low-pass filter of the T configuration. It is known that such a network, when properly proportioned, can be put to use as an impedance transformer; when the network is matched to the internal impedance of the driver at one end and to the load impedance at the other the maximum transfer of energy is achieved.

70 In the present invention, it is desired to extend the low frequency response below the point at which it starts to fall off in a closed box. This lower cutoff point occurs when the inertances of the loudspeaker and the associated air load resonate with the compliances of the speaker suspension and the closed box, in series. This

resonance occurs at a frequency higher than the primary free air resonance of the loudspeaker.

Referring now more particularly to FIG. 6 wherein impedances expressed in decibels are plotted as ordinates and frequency in cycles per second as abscissas, curve A illustrates the rise in the motional impedance of a typical electromagnetic loudspeaker at its free air resonance point f_2 . Curve B shows the similar free air performance with a damping ring (such as 21 in FIGS. 1 and 2) attached to the speaker near the back $20b$ of the diaphragm. Curve C shows the variation in motional impedance of the same loudspeaker within the enclosure of FIGS. 1 and 2 with the damping ring 21 in place. These motional impedances appear as voltages at the terminals of the loudspeaker voice coil. Four frequency points are marked in FIG. 6:

f_1 =series resonance of M_s , C_s , M_t and M_m (of FIG. 5)

f_2 =series resonance of M_s with C_s in free air

f_3 =series resonance of M_s , C_s , M_t , and C_b

f_4 =antiresonance of series branch M_s , C_s and M_t and shunt branch C_bM_m

The effect of the damping ring 21, as shown in curve B is clear. It has reduced the impedance hump by approximately two to one. The antiresonant effect of the quarter wave air column as shown in curve C is also clear. Since the velocities of the diaphragm and the antiresonant air column at the throat are in phase opposition, the excursion of the diaphragm f_2 is reduced to its normal level. This in turn reduces harmonic distortion arising from nonlinearities in the loudspeaker system and maximizes radiation at the mouth terminus 32a.

I claim:

A loudspeaker enclosure for use along a vertical room wall and in spaced relation to the room floor having a plurality of spaced vertical wall panels including two

side wall panels and front and rear wall panels, said vertical wall panels being vertically connected and one of said side wall panels extending downwardly to the room floor, a top wall panel closing said vertical panels, a baffle member connected to one of said vertical panels and to an opposed pair of said vertical panels and extending upwardly and terminated in spaced relationship to said top wall panel, said baffle providing on one face thereof with its connected vertical panels an interior throat portion and on the other face thereof with said opposite pair of connected vertical panels and with an opposing vertical panel an intermediate passage portion, the space within said vertical panels and above said baffle and below said top wall panel providing an energy sink in communication with said interior throat portion and with said intermediate passage portion, said energy sink being larger than said interior throat portion, the space below said vertical wall panels and to the room floor providing a mouth portion terminating immediately below said vertical panels, and a loudspeaker mounted at one side of said throat portion and having at least one diaphragm face thereof in communication with said throat portion, said interior throat, energy sink, intermediate passage and mouth portions providing a folded air column no greater in length than a quarter wave of sound in air at the primary resonance frequency of said loudspeaker.
